CLAIM

I claim the ornamental design for a charger for electronic cigarette, as shown and described.

DESCRIPTION

FIG. 1 is a front elevation view of a charger for electronic cigarette of the present invention;

FIG. 2 is a back elevation view thereof;

FIG. 3 is a side elevation view thereof;

FIG. 4 is a top plan view thereof;

FIG. 5 is a bottom plan view thereof; and,

FIG. 6 is a top perspective view thereof.

The ornamental design which is claimed is shown in solid lines in the drawings. The broken lines showing the charging ports in FIGS. 1-6 of the drawings are included for the purpose of illustrating environmental structure and form no part of the claimed design.
